John Eckert Greenawalt, Bronxville, N.Y., assignor to Greenawalt Sintering Co., Inc., New York, N.Y., a corporation of New York

Filed Sept. 5, 1961, Ser. No. 135,807

5 Claims. (Cl. 230—128)

This invention relates to centrifugal blowers or fans and, more particularly, to improved diffusers for obtaining increased pressure or suction.

In one conventional type of blower used for example, for applying suction to a sintering machine, the blower comprises an involute chamber surrounding a diffuser which in turn surrounds the impeller. Rotation of the impeller draws gases axially of the impeller into its blades, and the blades discharge such gases through the diffuser into the involute chamber, whence the gases are discharged from the blower. In such blowers as heretofore constructed, the cut-off edges of the diffuser blades are comparatively sharp and narrow as measured in a circumferential direction. According to a preferred form of the present invention, these cut-off edges are extended circumferentially beyond the cut-off point for a considerable distance, comparable to the distance between impeller blades. This construction provides a more positive seal to the flow of gases between diffuser nozzles, and has other advantages as will be more apparent as the description proceeds.

Objects of the present invention are thus to improve the amount of suction obtained from such a blower, and in general to improve construction and operation of gas blowers or compressors.

Other objects and features of the invention will be more apparent from the following description when considered with the following drawings in which:

FIG. 1 is a front elevation, with parts broken away, of a blower according to the invention;

FIG. 2 is a vertical cross-section through the blower, taken on the line 2—2 of FIG. 1;

FIG. 3 is a plan section with top of the housing removed, taken on line 3—3 of FIG. 2;

FIG. 4 is a side elevation of one of the fan disks for cooling the blower bearings;

FIG. 5 is an end elevation of the fan disk of FIG. 4;

FIG. 6 is a section taken through the diffuser, shown disassembled from the blower, taken on a plane perpendicular to the blower axis;

FIGS. 7 to 12 are detail sections, taken on the lines 7—7 to 12—12 respectively of FIG. 6, illustrating the construction of the diffuser nozzles.

In the following description and in the claims, various details will be identified by specific names for convenience, but they are intended to be as generic in their application as the art will permit.

Like reference characters denote like parts in the several figures of the drawings.

In the accompanying drawings and description forming part of this specification, certain specific disclosure of the invention is made for purposes of explanation, but it will be understood that the details may be modified in various respects without departure from the broad aspect of the invention.

Referring now to the drawings, and more particularly to FIGS. 1, 2 and 3, the blower will first be only generally described. As illustrated, it rests at a foundation 10 which has a high tower block 11 for electric drive motor 18.

The blower comprises a frame or housing 12 having a diffuser 35 surrounding an impeller 13. The impeller is mounted on main shaft 14 which is journaled in bearing

2

ings 16 and 17. Shaft 14 is connected to the shaft of motor 18 by coupling 19. Shaft 14 supports fan disks 20, 21 for cooling the bearings 16 and 17. The blower has a bottom inlet passage 22 in register with an opening 5 passing through the foundation 10, and a discharge passage 23 at the front of the blower.

The blower will now be described more in detail. The housing 12 is split vertically into right and left sections, and is split horizontally into a base 29 and top 30. The right and left sections are connected by bolted coupling flanges 27 and the base 29 and top 30 are connected by bolted coupling flanges 28, as will be understood by those skilled in the art.

The base 29 comprises ribbed walls 31, 32; these support the blower bearings 16 and 17. The housing 12 comprises an involute or flaring scroll 36, whose larger end connects with front discharge 23 and whose smaller end is separated from discharge 23 by a removable baffle 33.

The involute 36 is generally rectangular in cross-section, 15 as shown in FIG. 1, and its cross-sectional area flares as shown in FIG. 2. It has annular radial sealing flanges 37 which enclose the discharge ends of the impeller blades 50 as described more at length below. The bottom inlet 22 connects with inlet passages 34 which straddle the involute 20 36 and connect with circular entrance chambers 38 disposed on either side of the impeller 13.

Referring now also to FIGS. 6 to 12, the diffuser 35 is 20 made in two half sections connected by coupling flanges 41. The diffuser has a series of spiral blades 40 forming diverging or flaring nozzles 42. The inner or entrance ends of blades 40 have extended separating surfaces or lands 43. The lands 43 extend from the shearing edges 45 circumferentially for considerable distances, and are laid out on a fixed radius whose center 14a is a center of 25 shaft 14. These lands 43 are discussed more at length below.

The inner edges of the diffuser 35 have annular flanges 44 which rest upon seats 46 of the involute 36. The sealing flanges 37 and diffuser 35 form a runway for the 30 impeller blades 50.

The wheel or impeller 13 has a hub 47 keyed to shaft 14. It has a central plate-like member 48 with projecting web extensions 52 and a series of radial blades 50. The inner or entrance ends of the blades are tapered as at 49 (FIG. 1). The outer or discharge ends of the 35 blades 50 fit in the runway between the sealing flanges 37, as indicated especially in FIGS. 1 and 3.

The clearance spaces or gaps between the impeller blades 50, on the one hand, and the sealing flanges 37 and the lands 43, on the other hand, are as thin as is practicable.

The housing 12 has seals 51 where the shaft 14 passes through. Adjacent these seals are heat-conducting fan disks 20, 21. These disks are preferably made of copper or other good heat-conducting material.

55 The heat-conducting fan disks 20 and 21 are identical except that one is right handed and the other is left handed; hence, only one will be described in detail. The disk is split at 53. Each disk comprises a hub 54 rigidly secured to the shaft 14, blades 55 and openings 56. The 60 blades 55 are arranged at such angle that the fan disks generate currents of air which flow in a direction toward their respective bearings 16 and 17.

In operation, the electric motor 18 drives the impeller 13 in the direction of the arrow 58 in FIG. 2. 65 Gas is drawn in through the bottom inlet 22 through the dual inlet passages 34, and into the inlet chambers 38 at either end of the impeller 13. Air is drawn in by the impeller blades 50 and discharged from them into the nozzles 42 of the diffuser 35 and delivered to the involute 36 and thence to front discharge 23.

As stated above, an important feature of the invention

tion is the extended cut-off surfaces or lands 43 on the diffuser. In similar blowers, as heretofore constructed, the cut-off edges of the diffuser blades were sharp and narrow (in a circumferential direction) whereas in the present blower, the cut-off surfaces or lands 43 are extended circumferentially beyond the cut-off points 45 for a considerable distance.

To obtain the most desirable results the circumferential length of the lands 43 should equal the peripheral distance between the ends of the impeller blades as shown in FIG. 2. However, the maximum length of the lands should not exceed one-half the distance between the cut-off or shear points 45 of successive blades of the diffuser.

By way of further explanation of the operation of a blower constructed according to the invention, it may be noted that during the time the blades 50 pass over the surface of lands 43, the outward flow of gases near the surface of the blades is halted for an instant or very brief time and thereby the gases adjacent the blades receive the full velocity of the blades 50, so that a substantial length of the lands is necessary for most efficient results. As the length of the lands is decreased, the effectiveness of the desired action is decreased but even an increase of 15% in length of the lands beyond the shear points 45 produces materially better results than the sharp or narrow cut-off edges of the diffusers of prior art blowers.

The following further explanation of the function of the extended lands 43 is given in an effort to clarify the operation of the invention and should not be interpreted in a limiting sense. Regardless of theory, the operation is greatly improved as shown by the tests described hereinafter.

The improved operation is also thought to be due, at least in part, to the fact that the lands 43, and the small clearance between tips of the impeller blades 50 and the surfaces of the lands, reduces to a minimum the recirculation of air between the blades of the impeller 13 and the blades of the diffuser 35. This creates a more positive seal to the flow of gases. During the time the impeller blades 50 pass over the lands 43, the discharge flow of gas from the impeller is partially blocked or obstructed so that the centrifugal force applied by the impeller produces localized compressions. This increases the delivered static pressure or suction of the blower and improves efficiency.

The following tests show the effectiveness of the extended lands 43, as compared with the sharp cut-off edges of the prior art. Both tests were made with two blowers in series. In both cases blowers were the same except for the diffusers; the temperature of the gases was approximately 350° F. and the power consumption and volume flow rate were the same.

With the regular or standard diffuser, with the sharp cut-off edges, the resulting suction of the two fans in series maintained a column of water 70 inches high, whereas, with the improved diffuser of the invention, the resulting suction of the two fans in series maintained a column of water 80 inches high.

The dimensions and proportions of the several parts may be varied widely according to power, rotational speed, suction, pressure and volume desired. As an example, in the form shown which is designed for a sintering machine operation, the impeller 13 has a speed of from 1500 to 1700 r.p.m. The motor 18 is 800 H.P. The impeller diameter is 63 inches. The end clearance of the impeller blades with the lands 43 is one-quarter of an inch. The lands 43 are 13.5 inches in length (circumferentially of impeller movement), and the blades are 18 inches wide at their ends (axially of shaft 14). There are 14 impeller blades 50 and 6 diffuser blades 40.

While certain novel features of the invention have been disclosed herein, and are pointed out in the annexed claims, it will be understood that, in accordance with

the doctrine of equivalents, various omissions, substitutions and changes may be made by those skilled in the art without departing from the spirit of the invention.

What is claimed is:

5 1. In a blower for moving gases to provide a suction on the intake side, a housing, an impeller journaled for rotation in said housing, said impeller having radially disposed blades, said impeller blades having entrance ends and discharge ends, a diffuser comprising a plurality of spiral blades forming spiral, outwardly flared discharge nozzles therebetween, said diffuser blades having inner entrance ends and discharge outer ends, said diffuser blades entrance ends being disposed adjacent said impeller blades discharge ends and each having a land extending a substantial distance circumferentially from its innermost cutoff edge, said lands having a fixed radius throughout their lengths measured from the axis of rotation of said impeller and the circumferential length of each of said lands not exceeding one half the circumferential distance between the cutoff edges of successive diffuser blades, said housing being involute in shape and having an entrance chamber adjacent said impeller blade entrance ends, said housing having a discharge chamber adjacent the discharge ends of said diffuser nozzles, said diffuser being further characterized by its fixed radius lands having constant clearance gaps between the discharge ends of the impeller blades throughout the lengths of said lands and said lands being of sufficient length in relation to the distance between tip ends of successive impeller blades and said clearance gaps being sufficiently small to briefly halt outward flow of gases moved by said impeller so that the gases moving adjacent the impeller blades receive the full angular velocity of the tip ends of the impeller blades prior to entering said spiral discharge nozzles.

2. In a blower of claim 1 the circumferential length of said lands being approximately equal to the distance between the tip ends of successive impeller blades and the circumferential distance between the cutoff edges of successive diffuser blades being at least twice the circumferential length of said lands.

3. In a blower of claim 2 the circumferential length of said lands being between 15% and 50% of the circumferential distance between the cutoff edges of successive diffuser blades.

4. In a suction blower, for moving gases, a housing, an impeller journaled for rotation in said housing, said impeller having a central web with radially disposed blades extending on either side thereof and outwardly thereof, 50 said housing comprising an involute discharge chamber surrounding the tip ends of the blades of the impeller, said discharge chamber having an inner wall, said inner wall having sealing flanges having seats and disposed on either side of said impeller blades providing a circular runway for said impeller blades, said housing having entrance chambers defined by said sealing flanges, said entrance chambers being located on each side of said impeller, a diffuser surrounding said inner wall adjacent said sealing flanges, said diffuser comprising a plurality of spiral blades seated in said seats and forming divergent spiral discharge nozzles therebetween, said diffuser blades at their inner ends having lands disposed outwardly of and adjacent the tips of said impeller blades, said lands extending a substantial distance circumferentially, and throughout 55 their lengths having the same radius measured from the axis of the rotation of said impeller thereby providing constant clearance with the tips of said impeller blades throughout the circumferential lengths of said lands, and each of said lands having a circumferential length of at least 15% but not exceeding 50% of the circumferential distance between the cutoff edges of successive diffuser blades, the circumferential distance between the tip ends of successive radial blades of said impeller being substantially less than the circumferential distance between the cutoff edges of successive diffuser blades, whereby the flow

of gases moved by said impeller radially outward is briefly halted by said lands so that there is imparted to the gases moving adjacent the impeller blades the full angular velocity of the tip ends of said impeller blades prior to the discharge of said moving gases into said spiral discharge nozzles.

5. In the suction blower of claim 4, said lands having a circumferential length approximately equal to the circumferential distance between the tip ends of successive impeller blades.
